UNITED STATES PATENT OFFICE.

HENRY A. DREFEIN, OF CHICAGO, ILLINOIS.

FUEL AGITATOR FOR GAS PRODUCERS.

Application filed October 12, 1918. Serial No. 257,906.

To all whom it may concern:

Be it known that I, HENRY A. DREFEIN, a citizen of the United States, residing at Chicago, in the county of Cook and State 5 of Illinois, have invented certain new and useful Improvements in Fuel Agitators for Gas Producers, of which the following is a specification.

This invention relates to improvements in 10 gas producers, and its purpose is to provide a tamper and spreader of novel form for spreading the fuel and maintaining the fuel bed in a solid condition by preventing the occurrence of blow-holes and the caking of 15 the fuel. An important object of the invention is to provide a differential tamper and spreader for automatically spreading and tamping the fuel. Another object is to provide an improved stirring device actuated 20 by automatic driving means of novel design. Other objects relate to various features of construction and arrangement which will appear more fully hereinafter.

The nature of the invention will be understood 25 from the following specification taken with the accompanying drawings in which one embodiment is illustrated.

In the drawings—

Figure 1 shows a vertical section through 30 the upper part of a gas producer taken along the line 1—1 of Fig. 2 embodying the features of my invention;

Fig. 2 shows an enlarged top plan view of 35 the driving mechanism with a portion thereof removed;

Fig. 3 shows an enlarged vertical section through the upper end of the vertical stem of the stirring device; and

Fig. 4 shows an enlarged horizontal section 40 taken on the line 4—4 of Fig. 1, looking in the direction of the arrows.

Fig. 5 is a horizontal section through the supporting bracket.

Fig. 6 is a horizontal section through the 45 agitator stem in a plane just above the rotation effecting ratchet.

In the accompanying drawings, I have 50 illustrated the invention as applied to a gas producer having a shell or casing 10, consisting of a steel outer wall lined with fire-brick, or the like, provided with a downwardly converging lower portion 10^a resting upon a suitable bed 11 containing the usual water seal, and other parts which do 55 not form a part of the present invention.

The brick-work in the upper portion of the shell is inclined upwardly and inwardly, as shown at 12, and a gas flue or chimney outlet is provided at 13. The upper end of the shell is closed by the upper wall 14, by which the parts forming the present invention are supported. Suitable conical poke holes 15 are provided in the upper wall, one of these being shown in Fig. 1, for example, and these holes are normally closed by removable caps 16. Fuel is introduced into the gas producer through a hopper 17, which extends through the upper wall and is provided with a fuel-distributing gate 18 suspended in the lower portion thereof 60 on a rod 19, which is pivotally connected at its upper end to one end of the lever 20, carrying the counterbalancing weight 21. The upper surface of the gate 18 is inclined 65 inwardly toward the center of the producer, 70 so that the fuel passing therethrough is automatically directed toward the center of the fuel bed, which is designated by the numeral 22.

For the purpose of stirring the fuel bed 80 22, and maintaining the same in a solid condition, I have provided a stirring device 25 comprising the oppositely directed or radiating arms 26 carried at the lower end of a vertically-extending rod or stem 27. 85

The arms 26 are provided with encircling bands 28 which are tapered, as shown, to provide sharp projections to extend downwardly into the fuel bed. The vertical rod or stem 27 of the stirring device extends 90 through a bearing sleeve 29 which is carried by a metal frame or casting 30 seated in the upper wall 14 and forming a support for the hopper 17 which opens therethrough. The stem 27 is provided with two 95 concentric ducts 27^x, 27^y extending therethrough and communicating with similar concentric ducts in the radiating arms 26. Cold water or some other cooling medium is supplied to the central duct 27^x of the stem 27 at the upper end thereof through 100 a pipe 31 connected by a flexible tube 32 to a supply pipe 33. A cap 34 closes the upper end of the rod 27 and the pipe 31 is provided with a swing joint 31^a to permit rotation of the rod 27. The cooling fluid flows downwardly through the central duct of the stem 27 and then to the central ducts of the radiating arms. The 105 central ducts of the radiating arms termi- 110

nate short of the ends of the arms, so that the fluid flows outwardly at these points into the outside concentric ducts through which it returns back to the stem 27, and 5 thence upwardly to the outlet spouts 35. The cooling fluid flows outwardly through these spouts 35 and downwardly into a collecting cup or vessel 36 mounted around the stem 27 above the upper wall 14. An 10 outlet pipe 37 extends downwardly from the cup 36, being provided with a valve 38 and a tee connection 39, and the lower end of this pipe communicates with an aperture 40 in the lower wall of the metal frame or 15 casting 30. The water flows downwardly through the aperture 40 into a combined supporting and cooling bracket 41, which is provided at its lower part with a bearing portion 42 extending around the stem 27 20 some distance below the upper wall of the shell or casing 10. This bracket 41 is hollow and is provided with a partition 43 which extends downwardly to the bottom thereof, so that the cooling fluid flows down- 25 wardly at one side of the partition, then around through the hollow bearing portion 42, and then upwardly at the other side of the partition, where it passes through an opening into the drain channels 44 30 formed within the hollow frame or casting 30. These drain channels surround the bearing 29 and the walls of the hopper 17 in order to maintain these parts in a cool condition, and the water then flows off by 35 gravity through an outlet pipe 46 from which it may be conducted downwardly into the water seal of the bed 11 or to any other desired place. In order to clean out the cooling bracket 41, the valve 38 may be 40 closed and a steam pipe attached to the tee connection 39, so that a jet of steam can be blown through the hollow bracket.

For the purpose of rotating the stirring device 25 and reciprocating the same in a 45 vertical direction, actuating mechanism is provided in connection with the upper part of the stem 27. This actuating mechanism is carried by a supporting post or casting 50 which partially surrounds the stem 27, and the cup 36 being secured at its lower 55 end to the plate 30 which is seated in the upper wall 14. The casting 50 carries at its upper end a horizontal plate 51 having a bearing 52, in which the rod 27 is journalled and the plate 51 has secured thereto a cup-shaped cover plate or housing 53 which carries another bearing 54 for the rod 27. Within the housing formed by the plate 51 and the cover plate 53 are two ratchet wheels 55 and 56 having different numbers of teeth. The lower and smaller ratchet wheel 56, having the larger number of teeth, has a threaded engagement with the spiral groove or thread 57 60 which is formed in the stem 27. The up-

per and larger ratchet wheel 55 having the smaller number of teeth is splined on the rod by means of a key portion 55^a slidably engaging a keyway 58 in the rod, so that the rotation of the ratchet wheel rotates 70 the rod while permitting vertical movement thereof. The two ratchet wheels bear upon each other and are maintained between the bearings 52 and 54, so that rotation of the ratchet wheel 56 normally tends to cause 75 a vertical movement of the stem 27. The ratchet wheels are rotated by suitable operating mechanism mounted on a table or plate 60 which extends outwardly from the plate 51. An electric motor, or the like, 80 61 is mounted on the table 60 and is connected through a shaft 62 with a speed changing device 63 having its shaft 64 connected to a crank shaft 65 mounted to rotate in bearings 66 carried by the plate 60. 85 The crank shaft 65 has two crank arms, one crank arm being connected to a connecting rod 67 which is pivoted at 68 to a rod 69, which slides in a sleeve 70, and is pivotally connected at its other end to a pawl 71 90 adapted to engage the teeth of the lower ratchet wheel 56, the pawl being normally forced into engagement with the teeth by a leaf-spring 72. The other crank arm of the shaft 65 is connected to another connecting rod 74 which is pivoted at 75 to a rod 76, which slides in a sleeve 77 and is pivotally connected at its other end to a pawl 78 which is normally forced into 95 engagement with the teeth of the ratchet wheel 55 by means of a leaf-spring 79. These pawls and connecting rods normally advance the ratchet wheel in an amount equal to the pitch of a tooth in each cycle of the crank shaft 65. The two bearing sleeves 70 and 77 are formed on a bracket 51^a which is mounted on the table or plate 51. The connecting rod 74 is made extensible by forming the rod in two sections 74^a and 74^b, which are resiliently connected. 100 These rods extend through the end walls 80 of a cylinder 81, the one portion 74^b being secured to one end wall, while the other portion 74^a slides through the other end and is connected to its other end by 105 a piston 82. A coil spring 83 is mounted between the piston 82 and one apertured end wall of the cylinder, so that when the resistance opposed to the turning of the ratchet wheel 55 is too great, the coil spring 110 83 will be compressed upon each rotation of the crank shaft without causing reciprocation of the rod 76.

In the operation of the apparatus, the motor 61 drives the crank shaft 65 and thus 115 operates the two pawls 71 and 78 which engage the teeth of the ratchet wheels 56 and 55, respectively, and cause them to rotate. While the lower ratchet wheel 56 is completing one revolution, the upper 120

ratchet wheel completes more than one revolution, since the two pawls are actuated simultaneously, and the upper ratchet wheel comprises a lesser number of teeth. 5 The more rapid rotation of the upper ratchet wheel, whereby the rod 27 is rotated faster than the lower ratchet wheel, causes the rod to advance downwardly by reason of its threaded engagement with the lower 10 ratchet wheel, thus forcing the radiating arms 26 downwardly along an arcuate path into or through the fire-bed, at the same time that the arms rotate and distribute the fuel. In case the arms 26, or the rings 28, 15 become embedded in the fuel to such an extent as to provide a relatively large resistance to the rotation of the stirring device, the upper ratchet wheel 55 remains stationary, and the portion 74^a of the connecting rod merely reciprocates in the cylinder 81 and intermittently compresses the spring 83. While the upper ratchet wheel 55 remains stationary, the lower ratchet wheel 56 continues to rotate, since the 20 connecting rod 67 by which it is operated is of rigid construction. This causes the lower ratchet wheel 56 to advance on the threads of the rods 27, thereby elevating the stirring device through or away from the fuel bed until the resistance to the rotation thereof is decreased sufficiently to be overcome by the resistance of the spring 83, whereupon the upper ratchet wheel 55 will 25 again begin to rotate, and will force the stirring device downwardly toward the fuel bed at the same time that the stirring device rotates. In this way, the stirring device is automatically actuated to move the arms 26 through a circular zig-zag path 30 due to the alternate rising and falling of the arms. The stirring device thus automatically overcomes the resistance to the rotation thereof, and the apparatus continues to operate and to distribute and 35 solidify the fuel while at the same time tamping it down regardless of the condition of the fire-bed or of obstacles therein. During this operation, the stirring device is maintained in a substantially cool condition 40 by the circulation of cooling fluid therethrough, and the fuel which is discharged into the casing of the gas producer is directed toward the center of the stirring device to be thrown outwardly thereby. If 45 desired, the two ratchet wheels may rotate at the same speed or varied in size and number of teeth to secure the most suitable mode of operation under particular conditions. 50 Although I have shown and described a single embodiment of the invention for purposes of illustration, it will be understood that it may be constructed in various different forms without departing from the 55 scope of the appended claims.

I claim:—

1. The combination in apparatus of the class described of a shell, a fuel agitator in such shell, means to positively move said agitator downwardly along an inclined 70 arcuate path into the fuel, said means being operative upon the prevention of further arcuate movement of such agitator by resistance thereto to move said agitator vertically upward. 75

2. The combination in apparatus of the class described of a shell, a fuel agitator mounted in said shell, a rotatable member operatively connected to said agitator to rotate the same, a second rotatable member 80 operatively connected to said agitator to normally move it longitudinally of its axis of rotation, and operating means for simultaneously rotating said members.

3. The combination in apparatus of the class described of a shell, a fuel agitator mounted in said shell, a rotatable member operatively connected to said agitator to rotate the same, a second rotatable member 85 operatively connected to said agitator to normally move it longitudinally of its axis of rotation, and operating means for simultaneously rotating said members, means associated with said driving means to automatically discontinue the rotation 90 of said first named rotatable member when the resistance to the rotation of said agitator exceeds a predetermined limit. 95

4. The combination in apparatus of the class described, of a shell, a fuel agitator 100 mounted in said shell, means for rotating said fuel agitator, and means for moving said fuel agitator toward the fuel bed when said first-named means is in operation and for automatically moving said fuel agitator 105 away from the fuel bed when the operation of said first-named means is arrested.

5. The combination in apparatus of the class described, of a shell, a fuel agitator mounted in said shell and having a stem 110 projecting therefrom, an operating member having a driving engagement with said stem to rotate said fuel agitator, said stem being movable longitudinally with respect to said operating member, a second operating 115 member having a threaded engagement with said stem, and means for simultaneously actuating said operating members.

6. The combination in apparatus of the class described, of a shell, a fuel agitator 120 mounted in said shell and having a stem projecting therefrom, an operating member having a driving engagement with said stem to rotate said fuel agitator, said stem being movable longitudinally with respect to said operating member, a second operating member having a threaded engagement with said stem, means for simultaneously actuating said operating members, and means for causing the operation of said first named 125 130

- operating member to be automatically arrested when the resistance to the rotation of said fuel agitator exceeds a predetermined limit.
5. The combination in apparatus of the class described, of a shell, a fuel agitator mounted in said shell and having a stem projecting therefrom, an operating member having a driving engagement with said stem 10 to rotate said fuel agitator, said stem being movable longitudinally with respect to said operating member, a second operating member having a threaded engagement with said stem, and means for simultaneously rotating said operating members with different angular velocities.
6. The combination in apparatus of the class described, of a shell, a fuel agitator mounted in said shell and having a stem 20 projecting therefrom, a ratchet wheel splined on said stem, a second ratchet wheel having a threaded engagement with said stem, and means for simultaneously rotating said ratchet wheels at different speeds.
7. The combination in apparatus of the class described, of a shell, a fuel agitator mounted in said shell and having a stem 30 projecting therefrom, a ratchet wheel splined on said stem, a second ratchet wheel having a threaded engagement with said stem, said ratchet wheels being provided with different numbers of teeth, pawls engaging said ratchet wheels, and means for simultaneously operating said pawls.
8. The combination in apparatus of the class described, of a shell, a fuel agitator mounted in said shell and having a stem 40 projecting therefrom, a ratchet wheel splined on said stem, a second ratchet wheel having a threaded engagement with said stem, said ratchet wheels being provided with different numbers of teeth, pawls engaging said ratchet wheels, a crank shaft mounted adjacent said ratchet wheels, connecting rods extending from said crank shaft to said pawls, and a motor for operating said crank shaft.
9. The combination in apparatus of the class described, of a shell, a fuel agitator mounted in said shell and having a stem 50 projecting therefrom, a ratchet wheel splined on said stem, a second ratchet wheel having a threaded engagement with said stem, said ratchet wheels being provided with different numbers of teeth, pawls engaging said ratchet wheels, a crank shaft mounted adjacent said ratchet wheels, connecting rods extending from said crank shaft to said pawls, and a motor for operating said crank shaft, and a speed-reducing device between said motor and said crank shaft.
10. The combination in apparatus of the class described, of a shell, a fuel agitator mounted in said shell and having an operating rod extending vertically through the upper wall of said shell, said operating rod 60 being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, and means for simultaneously actuating said pawls.
11. The combination in apparatus of the class described, of a shell, a fuel agitator mounted in said shell and having an operating rod 65 extending vertically through the upper wall of said shell, said operating rod being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, means for simultaneously actuating said pawls, said last-named means being adapted to permit the operation of said second-named ratchet wheel to be arrested 70 when the resistance to the rotation of said fuel agitator exceeds a predetermined limit.
12. The combination in apparatus of the class described, of a shell, a fuel agitator mounted in said shell and having an operating rod 75 extending vertically through the upper wall of said shell, said operating rod being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, means for simultaneously actuating said pawls, said last-named means being adapted to permit the operation of said second-named ratchet wheel to be arrested 80 when the resistance to the rotation of said fuel agitator exceeds a predetermined limit.
13. The combination in apparatus of the class described, of a shell, a fuel agitator mounted in said shell and having an operating rod 85 extending vertically through the upper wall of said shell, said operating rod being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, means for simultaneously actuating said pawls, said last-named means being adapted to permit the operation of said second-named ratchet wheel to be arrested 90 when the resistance to the rotation of said fuel agitator exceeds a predetermined limit.
14. The combination in apparatus of the class described, of a shell, a fuel agitator mounted in said shell and having an operating rod 95 extending vertically through the upper wall of said shell, said operating rod being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, connecting rods operatively connected to said pawls, and means for operating said connecting rods, one of said connecting rods by which said second-named ratchet wheel is operated being provided with an adjustable attachment for permitting the 100 extension thereof when the resistance to the rotation of said second-named ratchet wheel exceeds a predetermined limit.
15. The combination in apparatus of the class described, of a shell, a fuel agitator mounted in said shell and having an operating rod 105 extending vertically through the upper wall of said shell, said operating rod being provided with a spiral groove and a vertical keyway, a ratchet wheel having a part engaging said spiral groove, a second ratchet wheel having a part engaging said keyway, a housing for said ratchet wheels, means carried by said shell for supporting said housing, pawls engaging said ratchet wheels, connecting rods operatively connected to said pawls, and means for operating said connecting rods, one of said connecting rods by which said second-named ratchet wheel is operated being provided with an adjustable attachment for permitting the 110 extension thereof when the resistance to the rotation of said second-named ratchet wheel exceeds a predetermined limit.
- In testimony whereof, I have subscribed my name.
- HENRY A. DREFFEIN.
